UNITED STATES PATENT OFFICE.

ALAN WOOD, 3D, OF LOWER MERION TOWNSHIP, MONTGOMERY COUNTY,
AND HARRY A. LEWIS, OF NORRISTOWN, PENNSYLVANIA, ASSIGNORS
TO ALAN WOOD IRON & STEEL COMPANY, OF CONSHOHOCKEN, PENN-
SYLVANIA, A CORPORATION OF PENNSYLVANIA.

ROLLER STAMPING-MACHINE.

No. 800,348.

Specification of Letters Patent.

Patented Sept. 26, 1905.

Application filed January 20, 1905. Serial No. 241,993.

To all whom it may concern:

Be it known that we, ALAN WOOD, 3d, residing in Lower Merion township, and HARRY A. LEWIS, residing at Norristown, in the county of Montgomery and State of Pennsylvania, citizens of the United States, have jointly invented a new and useful Roller Stamping-Machine, of which the following is a specification.

Our invention contemplates the provision of a new and useful machine to be used in connection with the operation of a rolling-mill or a roller-table for stamping sheets, bars, or the like of any metal while hot with changeable distinguishing marks, and to this end use is made of a small roller which may contain changeable stamps and which is pressed upon the hot metallic sheet, bar, or the like as it passes on the roller-table or issues from the rolling-mill and which is slidable laterally, so to be capable of being operatively arranged at various points across the table or mill.

Objects of our improvements are, first, to provide simple, reliable, and comparatively inexpensive means for marking or stamping sheets, bars, or the like of any metal while hot and capable of being used in connection with the operation of a rolling-mill or a roller-table; second, to afford means for marking or stamping sheets, bars, or the like of any thickness as they issue from any part of the rolls in finishing or are being conveyed upon the roller-table along any line between the two edges or sides thereof; third, to provide a means for changing the stamps in order to stamp with distinguishing marks different kinds, qualities, heats, lots, shapes, or sizes of sheets, bars, or the like of any metal; fourth, to stamp the same along a straight line parallel with the edge thereof throughout their entire lengths at frequent and regular intervals and before shearing in order that each of the sheared pieces shall be impressed with the distinguishing stamps or marks.

The nature, characteristic features, and scope of the invention will be more fully understood from the following description, taken in connection with the accompanying drawings, forming part hereof, and in which—

Figure 1 is a side elevational view of a machine embodying features of the invention, showing the same in application to a rolling-mill and roller-tables. Fig. 2 is a top view of

the hydraulic cylinder, chain, and operating-valve shown in Fig. 1. Figs. 3 and 4 are respectively side and end views of the two parts of a small roller adapted to contain the changeable stamps. Fig. 5 is a perspective view of a stamp. Fig. 6 is a partial top sectional view of the machine without the hydraulic cylinder and chain and showing in part the rolling-mill. Fig. 7 is a perspective view of a retainer for holding the stamp-roller on its axle.

Similar letters refer to similar parts throughout the several views.

In the accompanying drawings the parts of a rolling-mill and roller-table to which the mechanism may be attached in order to stamp the hot metal as it comes from the rolls are represented as follows: R represents the rolls of the mills, with their different grooves and the bull-head pass for finishing light material. (Best shown in Fig. 6.) r represents the rollers of the roller-tables for handling the product. f represents parts of the fore-plates, and are for guiding ingots into the grooves of the rolls; and F is part of the rolling-mill housing to which the mechanism embodying the invention may be conveniently attached.

Hot metal is or may be delivered from different points across the described machine of different thicknesses; but the invention is not limited to the parts which have been explained, as they are represented to illustrate a convenient method of attaching and operating the mechanism embodying the invention.

The revoluble shaft A is shown as arranged to turn in a bearing E in the mill-housing F and in a similar bearing in the other mill-housing, Figs. 1 and 6. The sliding lever-arm B slides along the shaft A by means of a mechanism. (Best shown in Fig. 6.) Shaft A has two long grooves or keyways k' and k'' from end to end (passing through the housings) directly opposite each other. A key p (best made of bronze) on the lever-arm B fits into one of the keyways k' . The lever-arm may thus be slid horizontally along the shaft A without turning. A small chain or the like, X, (a part of which is not shown,) is fastened to the right end of the key p , runs along inside the keyway k' and over the sprocket-wheel S, which is attached to the end of shaft A. Thence it runs along inside the other keyway k'' and around

- sheave-wheel u , attached to the other end of shaft A, thence along keyway k' , and is fastened to the left end of key p . The sprocket-wheel S is geared to the handle T, which 5 drives the sprocket-wheel S. The lever-arm B can be slid back and forth over the roller-table and in front of the rolls, so that the hot metal sheets, bars, or the like can be stamped from whichever part of the rolling-mill they 10 issue in finishing. In order to slide the lever-arm B easily along shaft A by hand-power, it may be balanced. This may be accomplished either by a counterweight on end of B opposite to the end which carries the part e , as shown, or by swinging the lever-arm B to 15 a vertical position, thus avoiding friction of key p in its keyway. On the outer end of the lever-arm B the small roller Q is set upon an axle at right angles to the lever-arm.
- 20 To enable the use of changeable stamps, the roller Q is made in two pieces, a body-piece Q' and a nut-piece Q², as shown in Figs. 3 and 4. A conical interrupted triple thread t may be used to make the separation of the nut and 25 body of the roller quickly. By fitting them so that the thread t bottoms just before the nut is up looseness and shaking of the two roller parts against each other are prevented. The thread t should be left-hand. Fig. 3 shows 30 the recesses for the changeable stamps. These recesses a are located upon the edge of the body of the roller Q' and exposed by the removal of the nut end Q². There is a projecting key or round pin b on one side of each recess. The changeable stamps (shown in Fig. 35) are of a size to fit in the recesses a and have a round keyway, corresponding to the key or round pin b , to hold them firmly in place. The letter, figure, or device to be stamped 40 may be raised to extend above the surface of the roller about one-eighth of an inch. The recesses a may be made of unequal depth, so that the first and last stamps project about one thirty-second of an inch less beyond the 45 surface of the roller than the middle ones. By this means all the stamps print of nearly equal depth. In Fig. 3 there are shown two sets of recesses of four each on directly opposite sides of the roller. This enables the stamping of the 50 letters or numbers twice for every revolution of the roller Q. Other convenient and similar arrangements readily occur to those skilled in the art and may be used in lieu of the above-described arrangements for the holding of the 55 interchangeable stamps in the roller.
- Fig. 7 shows a convenient retainer for holding the roller Q on its axle. The retainer e consists of a nut with a short handle, having an interrupted thread, so that a quarter-turn 60 backward frees the retainer at once. The thread in the retainer should be right-hand, so that the rubbing of the roller Q, in which the thread is left-hand, tends to tighten both. By making the retainer small enough in diameter to enter the counterbore Q⁴ on nut

end Q² of roller Q and the boss of lever-arm B against which roller Q rubs too large to enter the operator will be prevented from putting the roller on the wrong way.

In order to keep the stamps cool and preserve their hardness, a small water-pipe W on the lever-arm B is arranged to throw its jet on the stamps in roller Q. The inner end of W is attached to a flexible rubber hose h, which connects with the supply-pipe. The 75 water-cock c, Fig. 1, in the supply-pipe is connected by a lever and link to the hydraulic operating-valve O, so that the water is turned on automatically when the machine is put in 80 operation.

The lever-arm B is operated by the mechanism best shown in Fig. 1. A wheel C is fastened to shaft A outside the housing F. The cast-iron plate G, in which the end of shaft A revolves in a bearing, is held in position by the round nut H, which screws on the hydraulic cylinder I, and also by a bracket lower down. (Not shown.) The block K is held firmly in place by being fitted into a notch in the plate G and by being bolted to hydraulic cylinder I. Connection D, a chain, is fastened to block K on the right-hand side, as by an adjusting eyebolt, and passes horizontally over sheave-wheel J' on end of hydraulic plunger J, thence around sheave-wheel L, which 95 is hung on the left end of block K, thence vertically up and around chain-wheel C, to which it is fastened by the pin N, which prevents the chain from slipping upon wheel C. A counterweight M is hung upon the end of 100 chain D. The hydraulic plunger J is operated by the cylinder I and is controlled by the hydraulic valve O.

The machine is operated by adjusting the lever-arm B and roller Q, containing the interchangeable stamps, by means of the handle T, so that it is on a line with the part of the rolls from which the sheets, bars, or ingots are to issue in finishing. The operating-valve O is then thrown open, and the plunger J, 105 pushing outward on the chain D, causes the wheel-shaft and lever-arm to turn and press the roller Q upon the hot metal as it passes beneath, thus stamping the metal from end to end with the numbers or letters set in the 110 roller Q. On releasing the hydraulic pressure the counterweight M raises the lever-arm B and returns the plunger J into its cylinder I. When the plunger J is at the bottom of cylinder, lever-arm B should stand upright. 115 Where the stamps are arranged, as in the accompanying drawings, to print one at a time in succession, it requires about six hundred to one thousand pounds actual pressure to stamp plainly with letters or figures of about 120 three-eighths of an inch in length.

The mechanism above described may be set upon a separate framework over a roller-table, or where no roller-table is used in connection with a rolling-mill it may be attached 125

to the rolling-mill or set upon a separate framework close thereto. It is adapted to the stamping of bars, sheets, or the like or any metal while hot when the same are being rolled or moved on a roller-table and may be used upon any shapes or sizes.

The changeable stamps may be letters, numerals, figures, trade-marks, or other designs, and the machine can conveniently be used for distinguishing by the stamping the different kinds, qualities, heats, lots, shapes, or sizes. The number and arrangement of the recesses and stamps may be readily altered from that shown in the above drawings, so as to stamp either crosswise or longitudinally or diagonally to the length of the sheet, bar, or the like as it passes beneath, and the intervals between each set of stamping may be regulated by the size of the roller, it being of course understood that in such case the number of stamps remain the same, so that the intervals between them will naturally be increased along with the length of the periphery.

While hydraulic power is used in the mechanism described above, any other power may be used for the rotating of the shaft and sliding lever-arm and for the pressing of the roller with interchangeable stamps upon the hot metal.

It will be obvious to those skilled in the arts to which the invention relates that modifications may be made in details without departing from the spirit thereof. Hence the invention is not limited further than the prior state of the art may require; but,

Having thus described the nature and objects of our invention, what we claim as new, and desire to secure by Letters Patent, is—

1. Means for marking bars and the like which comprise a pivotal arm, a marking-roller revolvably mounted on said arm, means for forcibly turning said arm, and devices for laterally adjusting said roller, substantially as described.

2. The combination of a revolvable shaft, an arm splined thereon, a marking-roller journaled near the end of said arm, devices for shifting the arm lengthwise of the shaft, and mechanism for turning the shaft for applying pressure to the roller, substantially as described.

3. The combination of a shaft having diametrically - disposed lengthwise - ranging grooves, an arm mounted on said shaft and provided with a key adapted to one of said grooves, sheaves at the ends of said shaft, a flexible connection running over said sheaves and arranged in said grooves and connected

with said arm, and means for shifting said connection, substantially as described.

4. The combination of a revolvable shaft provided with an arm, a marking-roller carried by the arm, a wheel applied to said shaft, a flexible connection engaging the wheel and provided with a counterweight, and a hydraulic piston and its connections in engagement with said flexible connection, substantially as described.

5. The combination of a revolvable shaft provided with an arm, a marking-roller at or near the end of the arm, a wheel carried by the shaft, a flexible connection secured to the wheel and provided at one end with a counterweight and having its other end firmly secured, a guide-sheave for said connection, a piston adapted to operate upon a bight in said connection, and means for operating the piston, substantially as described.

6. The combination of a pivotal arm provided at or near its end with a marking-roller, pipe connections for supplying water to the roller, mechanism for exerting pressure upon the roller, and a controlling-handle and its connections whereby said water connections are brought into operation when said mechanism causes pressure to be exerted on the roller, substantially as described.

7. The combination of a revolvable shaft provided on opposite sides with longitudinal slots, an arm splined to said shaft, a flexible connection attached to the arm and provided with means for operating it to shift the arm, a wheel fast on said shaft, a flexible connection secured to the wheel, and means for shifting the last-mentioned connection to turn the wheel, substantially as described.

8. The combination of a revolvable shaft, an arm slideable on the shaft and rotatable therewith, means for turning the shaft, devices for sliding the arm, and a marking-roller carried by the arm, substantially as described.

9. The combination of a roller consisting of two parts detachably connected, type exchangeably clamped between said parts, a revolvable shaft, an arm carrying said roller and slidably mounted on said shaft, means for positioning the arm, and devices for turning the shaft, substantially as described.

In testimony whereof we have hereunto signed our names.

ALAN WOOD, 3d.
HARRY A. LEWIS.

In presence of—

JOHN P. FOLEY,
CLEMENT B. WOOD.
